UNITED STATES PATENT OFFICE

EDGAR BOURQUIN, OF FRAMINGHAM, MASSACHUSETTS, ASSIGNOR TO WARREN TELE-
CHRON COMPANY, A CORPORATION OF MAINE

DESIGN FOR A CLOCK CASE

Application filed October 3, 1930. Serial No. 37,125. Term of patent 14 years.

To all whom it may concern:

Be it known that I, EDGAR BOURQUIN, a citizen of the United States, residing at Framingham, in the county of Middlesex, State of Massachusetts, have invented a new, original, and ornamental Design for a Clock Case, of which the following is a specification, reference being had to the accompanying drawing, forming a part thereof. Fig.

1 of the drawing is a front perspective view of a clock case showing my new design and Fig. 2 shows a side view thereof.

I claim:

The ornamental design for a clock case as shown.

In witness whereof I have hereunto set my hand this 26th day of Sept., 1930.

EDGAR BOURQUIN.
